UNITED STATES PATENT OFFICE.

GEORGE E. WOOD, OF PLANTSVILLE, AND EDMUND A. SCHADE, OF NEW BRITAIN, CONNECTICUT, ASSIGNORS TO THE STANLEY RULE & LEVEL COMPANY, OF NEW BRITAIN, CONNECTICUT, A CORPORATION OF CONNECTICUT.

DESIGN FOR AN ICE-PICK.

No. 38,900.

Specification for Design

Patented Nov. 26, 1907.

Application filed February 19, 1907. Serial No. 358,326. Term of patent 7 years.

To all whom it may concern:

Be it known that we, GEORGE E. WOOD and EDMUND A. SCHADE, citizens of the United States, residing at Plantsville, Hartford county, Connecticut, and New Britain, Hartford county, Connecticut, respectively, have invented a new, original, and ornamental Design for Ice-Picks, of which the following is a specification.

Our invention relates to a design for an ice pick.

In the accompanying drawings, Figure 1 is a side elevation. Fig. 2 is a plan view.

We claim:

The ornamental design for an ice pick, as shown.

GEORGE E. WOOD.
EDMUND A. SCHADE.
